Car Heater.

NO. 88,852.

Patented Apr. 13, 1869.

UNITED STATES PATENT OFFICE.

ARCHIBALD C. CRARY, OF UTICA, NEW YORK.

MODE OF WARMING RAILWAY-CARS.

Specification forming part of Letters Patent No. 88,852, dated April 13, 1869.

Be it known that I, ARCHIBALD C. CRARY, a resident of the city of Utica, in the State of New York, have invented a new and useful Improvement on the Mode or Process of Warming Railway-Cars by Steam.

My invention consists in constructing either above or below the main floor in each railway-car an additional floor or platform at such distance from the main floor as will of itself, in connection with the sides and main floor of the car, form a rectangular steam-chamber, or permit the occupation of the space between these floors by steam-pipes of sufficient size to contain the necessary quantities of steam to warm a railway-car, and, by means of the appliances herein below set forth, supply the boiler of a locomotive, or, when the steam-generator is used without the steam-engine, supply the steam-generator, with pure hot water; and I do hereby declare that the following is a full and exact description of the construction and operation of the same, reference being had to the accompanying drawings, and to the letters of reference marked thereon, making part of this specification, in which—

Figure 1 is a perspective view of a car, the seats and the flues under the seats, the hood, and socket designed to receive the end of the steam-pipe, which is connected with the steam-pipes of the next preceding car. Fig. 2 is a view of the steam-pipes and the cylinders at the corners of the cars. Fig. 3 represents the small cylinder and the valve attached to its lower end, which is inclosed in the large cylinder above named. Fig. 4 is a longitudinal elevation, showing the body of a car with the top removed to exhibit the steam-pipes and the cylinders at the lower corners of the car. Fig. 5 is a sectional view of the cylinders K and P and of the valve O in their relative positions.

A A A A, Fig. 1, are the seats in a railway-car. B B are the flues under the seats. C is the front platform. Under the platforms the induction and eduction pipes are situated.

F represents the hood. G is the socket in the center of the hood. E is the steam-pipe, which extends from the socket to the transverse pipe H. H H are the transverse, I I I I are the longitudinal, steam-pipes. J J J J

are the cylinders at the lower corner of the cars, through which the water flows from the steam-pipes to an air-tight tank, as set forth herein below.

The steam-pipes I I I I I and the transverse pipes H and H are hermetically joined to prevent the possibility of steam escaping in the cars in case of collision or other accident. I I I I I may be laid in equal numbers under each row of seats, and also in the center passage between the rows of seats. They may be laid under the floor, and be cased in by sheathing, made air-tight, and securely fastened to the joist on which the floor is laid; or these steam-pipes may be placed over the main floor and be incased, as stated above. The end or transverse steam-pipes are connected with the pipes which extend through the passenger-cars in equal number under each row of seats, and also through the center passage of each car. Over these pipes is an upper or false floor. On this false floor, and extending through the whole length of the space between the supporters or legs of each seat, is a flue and foot-rest, formed by securely fastening two triangular end pieces of these flues near the legs of the seats in a vertical position, and attaching to these end pieces two foot-boards, which shall at their upper edges approach within about two inches, and at their lower edges be firmly attached to the edge of an opening in the false floor, thus forming a flue under each seat, which will permit the heat from the steam-pipes to pass freely into the cars.

Cylinders J at the four corners of the car are firmly connected with pipes H H, and receive all the water condensed from the steam. When cylinders P are partly filled with water, cylinder K floats and raises valve O. This opens the aperture of the valve, and permits the water to escape from the car into the eduction-pipe M, and thence through the eduction-conduits into the air-tight tank.

G, Fig. 1 in Drawing 2, is a steam-chamber, which may be substituted for steam-pipes seen in Fig. 4 in Drawing 1. E, Fig. 1 in Drawing 2, is the intermediate between the steam-pipes of two adjoining cars, through which the drip or water condensed from steam is returned to an air-tight tank. F, Fig. 1 of

Drawing 2, is the induction steam-conduit, through which the steam passes into the steam-chamber or steam-pipes. L, Fig. 2 in Drawing 2, is a sectional view of the ball-valve. These valves may be substituted for valve J, described herein above. S, Fig. 2 in Drawing 2, is a sectional view of the steam-chamber. M, Fig. 2 in Drawing 2, is a sectional view of the great steam-pipes or leaders, through which the steam passes to the several cars on one side of the train of cars, and through which the drip or water condensed from the steam flows back on the opposite side of the train of cars to the tank. These large steam-pipes or leaders are, at each of their ends, connected with an induction or an education conduit; or intermediate between the cars, the valves in these conduits being similar to those described in Patent No. 87,472. The water is retained in the car to supply heat when the locomotive is temporarily detached. These pipes or leaders may be situated inside of the several cars, similarly to pipe L K M, Fig. 2, Drawing 1, or on the outside of a car, as seen in M, Fig. 2 of Drawing 2.

R and R R are the platforms. P P, Fig. 1 of Drawing 2, is a sectional view of cylinder J, (also seen in Drawing 1, in Fig. 2,) in which the ball-socket or valve L or cylinder K of Fig. 2 in Drawing 1 is situated.

Valve K and the ball-valve L are of less specific gravity than water, and are of greater specific gravity than steam. This causes them to rise when the water accumulates around them, and permits the water to escape into the conduit E with the force of the action of the steam.

The operations of the steam-chamber, the steam-pipes, and the intermediates or conduits between the cars, described hereinabove, are to condense the steam from the steam-generator and the escape-steam from the boiler, and to return the water condensed from the steam to

air-tight tanks, to be pumped into the boiler or steam-generator to be converted into steam, thus furnishing heat to the cars, and, by the use of pure water, avoiding the destruction of the boiler by the sulphur which is generally contained in water, and also avoiding the corrosion of the pipes in the boiler by lime. The air-tight tank is designed to add to the force of the steam the atmospheric pressure on the water in its passage from the steam-chamber and steam-pipes to the tank.

This invention constitutes a part of my apparatus for heating railroad-cars, for other portions of which Letters Patent have already been granted me in 1868 and 1869.

I am aware that some of the special devices which I use to carry out this part of my invention are not new with me, but the like arrangement for the like purpose has never before been made that I am aware of.

Having thus described my invention, what I claim therein as new and useful, and desire to secure by Letters Patent of the United States, is—

1. The application of the drip or water condensed from steam for the purpose of supplying pure water to the boiler or steam-generator and of warming railway-cars when the locomotive is temporarily detached from a train of cars, substantially as herein shown.
2. The float-valve, in connection with the return-pipe E, when used for the purpose set forth.
3. The foot-rest B, made as shown, when used as a register and foot-rest.
4. The combination of the double floor, constructed as set forth, the induction and education pipes, and valve and foot-rest, substantially as described.

ARCHIBALD C. CRARY.
